TRACK CONNECTER FOR TOY ELECTRIC RAILWAYS

Filed Feb. 10, 1931

INVENTOR.

Leon W. Rosenthal

UNITED STATES PATENT OFFICE

LEON W. ROSENTHAL, OF NEW YORK, N. Y.

TRACK CONNECTER FOR TOY ELECTRIC RAILWAYS

Application filed February 10, 1931. Serial No. 514,762.

This invention relates to toy electric railways, and more particularly to means for connecting track sections and track rails to each other, as well as means for facilitating an electrical connection to one or more of said rails or other track element.

One object of the present invention is to provide means for connecting track sections other than by directly joining abutting rails.

Another object is to provide improved means for connecting abutting rails.

And still another object is to provide means for facilitating an electrical connection to one or more of the rails or other track elements, as aforesaid.

In one embodiment it is arranged to connect track sections to each other by providing means for connecting the ties thereof. In another embodiment it is arranged to provide means for not only mechanically joining abutting rails but arranging that the connecting means shall comprise a wire terminal such as a phone cord tip. As to the third named feature it is arranged either to provide an element which may be readily attached to or detached from a rail or provide said rail with a portion arranged to engage a wire terminal of the nature aforesaid.

As in the case of the aforesaid pending application, it is arranged that the connector elements shall be individually and readily attachable and detachable or removable without requiring the separation of abutting track sections.

The features of invention above enumerated are illustrated in the accompanying drawing wherein,

Fig. 1 is a plan view of a toy electric railway track assembly (in part) incorporating various embodiments of my invention; Fig. 2 is an enlarged view of a part of Fig. 1 showing one embodiment; Fig. 3 is a vertical section on the line 3—3 of Fig. 2; Fig. 4 is a vertical section on line 4—4 of Fig. 3; Fig. 5 is a vertical section on the line 5—5 of Fig. 1; Fig. 6 is a vertical section on the line 6—6 of Fig. 5; Fig. 7 is an elevation showing another embodiment of my invention; Fig. 7a is a vertical section on the line a—a of Fig. 7; and Fig. 8 is still another embodiment

of my invention seen from the line 8—8 of Fig. 1.

Referring to Fig. 1 there is shown part of a track assembly consisting of three track sections 1, 2, 3 each comprising track rails 4, 4 and a power rail 5, held in spaced relation by end ties 6, 6 and intermediate tie 7.

In Figs. 2, 3 and 4, the contiguous end ties 6, 6 of abutting track sections 1, 2 are provided with straps, clips, clamps or other retaining means 8, 8 for receiving and clampingly engaging a connector element, such as pin 9, whereby the ties and hence the sections are joined to each other. The pin 9 is preferably provided with a transverse stud or projection 10 which upon rotation of said pin will have a cam action against the tie to more effectively secure said pin to said ties and prevent removal of said pin when in its operative position. The pin may be readily removed by rotating it through 90°, that is with the handle portion 11 vertically up and then sliding the pin out from said straps. The pins 9, 9 may be provided with a hole 12 into which may be inserted a wire terminal such as the phone cord tip 13. As shown in Figs. 1 and 2, the straps 8, 8 of the ties are arranged at an angle so that in rotating the handle portion from the vertical to the horizontal operative position, the said strap will act as a cam against the said handle portion to tend to draw the ties together and hold the same firmly and immovably in spaced relation. The stud 10 of course cooperates to make this camming action possible by preventing longitudinal displacement of the pin which would void the said camming action. Thus this arrangement acts very much to the same effect as the tie plates now in use so far as this latter aspect of the invention is concerned.

In Fig. 5 there are shown two abutting or contiguous rails at or near the abutting end of each of which there is formed integral with the rails a spring clip portion 14 or other equivalent arrangement for receiving and clampingly engaging a pin such as 9 or a phone cord tip such as 13 (Fig. 6). The abutting rails are joined by passing the pin or tip through the clip portion of said rails.

For providing a convenient means for merely making an electrical connection to one of the rails, the clip portion 14 may be formed along any desired joint of the rail 5 as shown in Fig. 8.

In Figs. 7 and 7a there is disclosed a terminal clip element or electrical connector 15 which is arranged to be clampingly attached or snapped on to a rail and is provided 10 with a part 16 integral with the element for receiving and clampingly retaining a phone cord tip 13 or other wire terminal.

Having described my invention, what I claim is:

15. 1. In a toy railway, a pair of contiguous sheet metal track elements having integral resilient means for receiving and clampingly retaining a common connector member, said means being so disposed with respect to 20 said elements as to allow said connector to be installed and removed without requiring separation of said elements from their normal relative positions.

25. 2. In a toy railway, a pair of contiguous sheet metal track elements including each a resilient clip formed integral therewith, and a common connector member arranged to be retained by said clips, said clips being so disposed with respect to said elements as to allow 30 said connector to be removed and installed without requiring separation of said elements from their normal relative positions.

35. 3. In a toy railway, a pair of abutting track sections each comprising a plurality of rails and a sheet metal tie near the abutting ends of said rails, said ties having integral, resilient means each for retaining a common connector member.

40. 4. In a toy railway, a pair of abutting track sections each comprising a plurality of rails and a sheet metal tie near the abutting ends of said rails, said ties including each a resilient clip formed integral therewith, and a common connector element retained by 45 said clips to join said ties to each other.

45. 5. In a toy railway, a pair of abutting sheet metal rails each having an exterior spring clip formed integral therewith at or near its abutting end and both clips being arranged 50 to retain a common connector member.

55. 6. In a toy railway, a pair of abutting sheet metal rails each having an exterior spring clip formed integral therewith at or near its abutting end, and a common connector retained by said clips.

7. A toy railway sheet metal track tie having a resilient clip formed integral therewith.

8. A toy rail of sheet metal having a resilient clip formed integral therewith and on 60 the outside of the rail.

9. In a toy railway, a pair of contiguous track elements, a common connector member therefor, and means integral with said elements for receiving said member, said member and said means being so arranged that in 65

securing it in operative position the said member will be cammed by said means to draw said elements together.

10. In a toy railway, a pair of contiguous track elements provided each with a strap at 70 least one of which is diagonal to the track, and a common connector member secured in said straps in cammed engagement with the diagonal strap.

11. In a toy railway, a pair of contiguous track elements provided each with a strap at least one of which is diagonal to the track, and a common connector member held by said straps and having a projection at each end, the projection at the end adjacent the diagonal strap being cammed by said diagonal strap to draw the projection on the other end against the side of the other strap to draw 75 said elements together.

12. In a toy railway, a pair of contiguous sheet metal ties having each a strap portion punched therefrom, and a common connector held by said straps.

13. In a toy railway, a pair of contiguous sheet metal ties having each a strap portion punched therefrom, at least one of which is diagonal to the tie, and a common connector member held by said straps and having a projection at each end, the projection at the end adjacent the diagonal strap being cammed by said diagonal to draw the other projection against the side of the strap adjacent thereto to draw said ties together.

14. A sheet metal toy rail having a head, web and flange portion with a spring clip 100 formed integral with the flange.

15. In a toy railway, a pair of abutting sheet metal rails each having a head, web and flange portion with a spring clip formed integral with the flanges at or near the abutting ends, and a common connector member engaged by said clips.

In testimony whereof I affix my signature.

LEON W. ROSENTHAL.
